UNITED STATES PATENT OFFICE.

JAMES FRANK TENNEY, OF CHICAGO, ILLINOIS.

DESIGN FOR A FONT OF PRINTING-TYPE.

SPECIFICATION forming part of Design No. 24,113, dated March 12, 1895.

Application filed December 27, 1894. Serial No. 533,129. Term of patent 3½ years.

To all whom it may concern:

Be it known that I, JAMES FRANK TENNEY, a citizen of the United States, and a resident of Chicago, county of Cook, and State of Illinois, have invented, produced, and set up a new and useful Design for a Font of Printing-Type, of which the following is a specification, reference being had to the accompanying drawing, showing a part thereof.

10 The drawing shows a face view of a font of type comprising the upper and lower cases.

The leading features of my design consist in the shape or configuration of the font of type delineated by the curved inner contours 15 *a, a, a, &c.*, which unite with the circular, curved and straight bars of the font of print-

ing type. The blank spaces inclosed, or partially inclosed within the type, are very conspicuous to the eye and present thereto curvilinear internal contours with circular, 20 curved, straight and angular exterior portions; and the blanks within the type *O, Q, upper case, and o, lower case* are respectively formed by two reversed curvilinear lines, as shown. 25

I claim—

The design for a font of printing-type, as herein shown and described.

JAMES FRANK TENNEY.
